HAIR CLIPPER

Reuben B. Anderson, St. Paul, Minn.

Application March 24, 1945, Serial No. 584,525

8 Claims. (Cl. 30—212)

1

My invention relates to an improvement in hair clippers wherein it is desired to provide a pair of clippers by means of which a person may readily trim his own hair.

Various types of hair clippers have been produced for trimming hair. These clippers are ordinarily used by barbers and others as a part of regular hair cutting operations. I have found, however, that it is virtually impossible with most clipper constructions for a person to operate these clippers for clipping the hair on the head of the operator. Thus while it is often convenient to trim the hair at frequent intervals, it is necessary with the usual construction of manually operated clippers to have this work done by an operator, it being practically impossible to hold the clippers properly to cut one's own hair.

I have found, however, that if the handles of the clippers are formed downwardly rather than upwardly and rearwardly as in usual construction it is possible to properly manipulate the clippers so that a person may trim his own hair. While this change is relatively simple, and while the clippers thus constructed would not be particularly advantageous for use by a barber, they are of extreme advantage to a person in trimming his own hair.

It is therefore the object of the present invention to provide a pair of clippers with downwardly and rearwardly extending handles so that the clippers may be operated successfully over any portion of the head to enable a person to trim his own hair. Such downwardly and rearwardly extending handles enable a person to manipulate the handles toward one another to provide the proper cutting operation in cutting one's own hair.

A further feature of the present invention lies in curving or inclining the cutting teeth of the clippers upwardly. With these simple changes clippers of a generally conventional type may be rendered useful for the intended purpose.

A further feature of the present invention resides in providing a pair of clippers with a fixed plate which is generally flat and which is provided with an upwardly curved or inclined forward cutting edge bearing teeth. The invention further includes a second plate slidable relative to the fixed plate and in close contact thereto which bears cooperating teeth. By sliding the second plate relative to the first plate the two sets of cooperating upwardly inclined teeth may operate to trim the hair.

A further feature of the invention resides in providing two cooperating tooth plates which

2

are relatively slidably supported and in providing handle means for sliding these plates relative to each other. The handle means is formed to extend substantially below the level of the major portions of the slidable plates. While the curved or upwardly inclined toothed portions of these plates lie substantially on a plane with the free ends of the handles.

These and other objects and novel features of my invention will be more clearly and fully set forth in the following specification and claims.

In the drawing forming a part of my specification:

Figure 1 is a perspective view of my clippers, a portion of the casing thereof being broken away to show the construction thereof.

Figure 2 is a rear elevational view of my clippers in readiness for use.

Figure 3 is a sectional view through the body of the clippers.

Figure 4 is a side elevational view of a modified form of clippers construction.

The clippers A include a hollow casing or enclosure 10 having a clipper handle 11 secured integrally thereto. As best illustrated in Figure 2 of the drawing the handle 10 extends upwardly and rearwardly from the casing or enclosure 10 in a manner similar to the curvature of the conventional handles for a pair of clippers. In other words, the handles 11 are provided with an upwardly and rearwardly extending portion 12 which curves at its upper extremity at 13 to merge into a downwardly and outwardly slanting handle portion 14. The handle portion 14 extends below the level of the base plate of the clippers which will be later described in detail.

The hollow enclosure or casing 10 is provided with a substantially flat lower edge 15 having a downwardly extending projection 16 at the rear thereof and a second downwardly extending projection 17 in the front thereof. The enclosure 10 is designed to enclose the pivot to which the second handle 19 is secured and to enclose the major portion of the reciprocable cutter blade.

A base plate 20 is secured to the housing 10 by means of a pivot bolt 21. This pivot bolt 21 is provided with a head 22 recessed into the undersurface of the base plate 20 and extends through the base plate and the top of the hollow casing 10. A washer 23 usually rests on the top of the casing 10 and the pivot bolt 21 is held in place by means of a wing nut 24.

In order to hold the base plate in proper spaced relation to the housing 10 and to pre-

vent the base plate from rotation relative to the housing, the downwardly extending projection 16 rests upon the upper surface of the base plate 20 and the projection 17 extends through a slot in the base plate. The projection 16 holds the base plate properly spaced from the housing while the projection 17 prevents rotation of the base plate about the pivot bolt 21.

A sleeve 25 is secured integrally with the casing 10 inwardly of the same and extends downwardly to encompass the pivot bolt 21. This sleeve 25 acts as a bearing for the hub 26 of the second handle lever 19. This handle lever 19 extends rearwardly through a notch 27 formed in the rear of the housing 10 and is provided with an upwardly and rearwardly extending handle portion 29 in opposed relation to the handle portion 12. The upwardly and rearwardly extending handle portion 29 terminates in a curved top portion 30 which connects the portion 29 with a downwardly and rearwardly extending handle 31 which is in opposed relation to the handle 14. Similarly to the handle end 14, the handle end 31 extends well below the base plate 20 of the clippers.

The handle 19 is provided with a forwardly projecting finger 32 integral with the handle hub 26. This finger 32 extends forwardly and downwardly into close proximity with the base plate 20 which terminates slightly above the level of the same. A spring 33 encircles the handle hub 26, one end of the spring being anchored to the handle 19 at the hub 34 and the other end of the spring being anchored to the casing 10 at the point 35. The spring 33 tends to hold the clipper handles 14 and 19 in the spaced relation illustrated, but permits the handles to be pivoted together about the pivot bolt 21, simultaneously increasing tension on the spring. The release of pressure tending to squeeze the handles together permits the spring 33 to urge the handles apart.

The forward end of the base plate 20 is curved upwardly as best illustrated at 36. The upwardly curved edge is provided with V-shaped teeth 37 best illustrated in Figure 1 of the drawing. In order to provide a cutting action a reciprocating cutter blade 39 is slidably mounted upon the base plate 20 and is designed for reciprocation by the handle 19.

The cutter blade 19 is slotted at 40 to accommodate the projection 17. The projection acts, together with the engagement of the forward edge of the housing 10 into the transverse slot 38 in the blade 39, to guide the cutter blade in its lateral movement. The surface between the reciprocable blade 39 and the base plate 20 is cut away to provide a pair of spaced sliding surfaces 41 and 42, one of which is at the rear edge of the cutter blade 39, and the other of which coincide with the upwardly curved forward ends of the base plate and cutter blade. A recess 43 is provided in the cutter blade to receive the finger 32 on the hub of the handle lever 19.

It will be noted that as the handle lever 19 is pivoted about the bolt 21 the finger 32 will force the cutter blade 39 laterally. As the cutter blade 39 is provided with an upwardly curved toothed edge 44 cooperable with the teeth 37, hair entering the teeth will be sheared off in the usual manner.

It will be noted that the upwardly curvature of the base plate 20 and the cutter blade 39 tends to present a smooth surface to the skin, although the base plate 20 is held at a considerable angle relative to the skin. The downwardly and rearwardly extending shape of the handle levers 14

and 19 makes it possible for a person to grasp the clippers in such a way that they may be manipulated properly over virtually any part of the head without difficulty. While clippers of the present design are probably not as convenient for use in clipping the hair of another as the usual type clippers, my clippers may be conveniently used by a person for cutting his own hair. While it is not necessary or entirely essential that the handles 14 and 19 extend upwardly and rearwardly before they curve downwardly, the construction illustrated is believed advantageous as it permits the clippers to be properly grasped without having the handles extend too far below the body of the clippers. Furthermore, it permits the handles to be of proper length for ease in manipulation without danger of having the handles project too low.

In Figure 4 of the drawing I disclose a modified form of construction which differs from the structure previously described in certain features. In this construction illustrated in general by the letter B, most of the structure is identical with the structure of the clippers A. Thus parts of the clippers B which are identical with similar parts of the clippers A will be given similar numerals while the different parts thereof will be given different numerals.

The clippers B include a hollow casing 10 which is secured to one clipper handle, not illustrated in the drawing. A pivot bolt 21 extends through a housing 10, being held in place by a wing nut 24. A second handle 19 is pivotally supported upon the pivot bolt 21 and a spring 33 urges the handle 19 in one extreme position.

A base plate 45 is secured to the housing 10 by the bolt 21. This plate differs from the base plate 20 only in the fact that the upper or toothed edge 46 thereof is not upwardly curved. A reciprocable cutter blade 47 is provided with a toothed edge 49 similar to the toothed edge 44 of the blade 39 except for the upward curve of the teeth. The remaining structure is very similar to that illustrated in the clippers A.

In order to compensate for the projection of the teeth in line with the base plate and to prevent these teeth from digging into the skin as the clippers move along the surface thereof I provide a bearing plate 50 beneath the base plate 45 and secured in place by the bolt 21. This bearing plate 50 is provided with an enlarged beaded edge 51 which is substantially below the level of the clipper teeth. As a result this rolled edge 51 travels over the surface of the skin and acts to space the teeth from the skin at the usual angle. In other words, the edge 51 of the plate 50 acts as a support for the clipper body during the operation of the clippers and the teeth may be swung closer to or farther from the skin so as to give the desired pressure.

It will be noted that my clippers are provided with handles of approximately the usual length so that they may be conveniently handled, and the main difference is that these handles extend downwardly and rearwardly rather than upwardly from the body in the usual way. The feature of curving the teeth upwardly or employing a bearing plate such as the plate 50 is also of importance in my invention.

In accordance with the patent statutes, I have described the principles of construction and operation of my clipper construction, and while I have endeavored to set forth the best embodiments thereof, I desire to have it understood that obvious changes may be made within the scope

of the following claims without departing from the spirit of my invention.

I claim:

1. A hair clippers construction including a body including a pair of relatively slidable clipper plates, handles secured to said plates to cause relative reciprocation, said handles extending downwardly and rearwardly to extend below the level of the cutter blades.

2. A clippers construction comprising a clipper head including a base plate, a pair of relatively pivotal levers secured to said clipper head for actuating the same, said handles extending downwardly and rearwardly relative to the clipper head to terminate below the level of said base plate.

3. A hair clippers construction comprising a clipper head including a base plate, a pair of relatively pivotal levers secured to said clipper head to actuate the same, said levers extending upwardly and rearwardly from said clipper head and terminating in downwardly and rearwardly extending handle ends.

4. A hair clippers construction comprising a clipper head including a base plate, a pair of relatively pivotal levers secured to said clipper head to actuate the same, said levers extending upwardly and rearwardly from said clipper head and terminating in downwardly and rearwardly extending handle ends, the ends of the handles being below the level of said base plate.

5. A hair clippers construction comprising a clipper head, a pair of relatively pivotal levers secured to said head to actuate the same, said levers each projecting from the rear of the head in opposed relation and extending upwardly and rearwardly from the head for a short distance, being rounded at their top extremity, and extend-

ing downwardly and rearwardly in opposed relation to terminate below the level of the clipper head.

6. A hair clipper construction comprising a clipper body, a handle secured thereto, a second handle pivotally attached thereto, a pair of toothed plates secured to said head, one of said plates being fixed with respect to the first named handle, and the other of said plates being reciprocably attached to the other handle, the teeth of said plates being upwardly curved, said handles extending downwardly and rearwardly from said clipper body.

7. A hair clipper construction comprising a clipper body, a handle secured thereto, a second handle pivotally attached thereto, a pair of toothed plates secured to said head, one of said plates being fixed with respect to the first named handle, and the other of said plates being reciprocably attached to the other handle, the teeth of said plates being upwardly curved, said handles extending upwardly and rearwardly for a short distance from said body and then extending downwardly and rearwardly therefrom.

8. A hair clipper construction comprising a clipper body, a handle secured thereto, a second handle pivotally attached thereto, a pair of toothed plates secured to said head, one of said plates being fixed with respect to the first named handle, and the other of said plates being reciprocably attached to the other handle, the teeth of said plates being upwardly curved, said handles extending upwardly and rearwardly for a short distance from said body and then extending downwardly and rearwardly therefrom to terminate below the level of said clipper head.

REUBEN B. ANDERSON.
